ATTORNEYS

UNITED STATES PATENT OFFICE.

MARK A. SMITH AND CHARLES F. YAEGER, OF EVANSVILLE, INDIANA.

DESIGN FOR A BROOM-SHIELD.

SPECIFICATION forming part of Design No. 17,177, dated March 8, 1887.

Application filed December 6, 1886. Serial No. 220,865. Term of patent 14 years.

To all whom it may concern:

Be it known that we, MARK A. SMITH and CHARLES F. YAEGER, citizens of the United States, residing at Evansville, in the county of 5 Vanderburg and State of Indiana, have invented and produced a new and original Design for Broom-Joint Shields; and we do declare the following to be a full, clear, and exact description of the same, reference being 10 had to the accompanying drawings, forming a part thereof.

Figure 1 of the drawings is a view of the shield. Fig. 2 is a perspective view. Fig. 3 is a part section.

15 Our design relates to a covering for broom-joints; and it consists in the novel form and configuration thereof, as hereinafter shown and described.

The leading features of our design are the representation of encircling corrugations and 20 the encircling grooves and the elliptic form therein. The covering A has the appearance of being composed of closely coiled or wrapped wire having the elliptic-shaped panel thereon.

What we claim is—

25 The design for a broom-shield herein shown and described, consisting of a representation of encircling corrugations and an elliptic-shaped panel therein.

In testimony whereof we affix our signatures 30 in presence of two witnesses.

MARK A. SMITH.

CHARLES F. YAEGER.
